UNITED STATES PATENT OFFICE.

PHILIP C. JACOBS, OF CHICAGO, ILLINOIS, ASSIGNOR TO H. W. JOHNS-MANVILLE COMPANY, A CORPORATION OF NEW YORK.

FLEXIBLE PIPE-COVERING.

1,329,409.

Specification of Letters Patent.

Patented Feb. 3, 1920.

Application filed November 6, 1919. Serial No. 336,162.

To all whom it may concern:

Be it known that I, PHILIP C. JACOBS, a citizen of the United States of America, residing at Chicago, county of Cook, State 5 of Illinois, have invented certain new and useful Improvements in Flexible Pipe-Coverings, of which the following is a specification.

My invention relates to a protective covering for pipes which covering is of low heat conductivity so as to reduce losses resulting from the conduction of heat to or from the contents of the pipe and is especially designed for use on small pipes which are 10 curved or bent and which require a flexible pipe covering which can be installed or built up upon them. Pipes of this kind, such as the numerous curved pipes employed in the cab of a modern locomotive, are also exposed 15 to frequent contact with the persons operating the locomotive and accordingly it is necessary that the pipe covering shall be tough and not easily fractured by blows or friction from passing persons or objects. My invention 20 meets all these requirements and is simple and economical. The preferred form of structure embodying my invention is illustrated in the accompanying sheet of drawings, in which—

30 Figure 1 is a vertical section through a pipe with my invention applied thereto, the parts being broken away;

Fig. 2 is a side view of the same, and

35 Fig. 3 is an enlarged detail cross section of the material which forms the basis of my covering.

Throughout the drawings, like reference characters indicate like parts.

1, is a section of steam pipe usually from 40 an inch to two and a half inches in diameter, which sizes are best adapted to receive my covering to advantage. 2, is a strip of special material wound spirally upon the pipe 1. This special material preferably consists of a strip of asbestos cloth 6, to which a somewhat thicker layer of flexible asbestos felt 8, is fastened by some mineral fireproof cement such as indicated by the thin line or layer 7, in Fig. 3. As shown, this strip is 45 wound upon the pipe with the felt face 8, next to the pipe, but of course it may be otherwise arranged. 3, is another strip of

plain asbestos cloth which is wound upon the covering 2, the spirals of the two strip windings running in opposite directions, as 55 clearly shown in Fig. 2.

To further bind and protect the covering, I next apply a spiral winding of wire 4, the spiral preferably running in the same direction as that of strip 2, and then to hold 60 this wire firmly in position and protect the cloth 3, and harden its exterior surface, I apply a thin covering of a fireproof cement 5, which dries on exposure to the air and becomes hard, thus protecting the insulation 65 beneath from abrasion, the action of the elements, and any tendency to unwrap. This in turn may be painted with a black asphaltic paint to make it conform to the 70 finish of any exposed iron piping in the locomotive cab or other compartment in which my invention is being employed. This asphaltic paint also gives waterproof quality to the outer covering. It may take the place entirely of the fireproof cement 5, in certain 75 cases. The paint film would be so thin and be so largely absorbed by the cement covering that I have been unable to show it clearly in the drawing.

The resultant covering so formed is of 80 low heat conductivity so that the loss of heat from the steam conveyed through the pipe 1, is much reduced and the operatives are protected from contact with the hot steam pipes. The materials employed in forming the cov- 85 ering are so flexible that they can be easily applied to the most sharply curved pipes in relatively inaccessible positions and yet be made to completely cover and thoroughly protect said pipes without leaving any gaps 90 or openings through which heat may escape.

Various subcombinations of the elements above enumerated might be employed without unnecessarily employing others mentioned and the modified structures so produced would still be within the scope of my invention although producing a somewhat less perfect result.

Having described my invention, I claim:

1, A built-up covering of low heat conductivity for curved steam pipes and the like, which comprises in combination a spirally wound strip of asbestos cloth to which a flexible strip of asbestos felt is attached 100

2 by a mineral cement, a covering strip of asbestos cloth spirally wound in the opposite direction, an external binding coil of wire and an external facing of fireproof cement 5 in which the wire is embedded.

2. A built-up covering of low heat conductivity for curved steam pipes and the like which comprises in combination an interior spirally wound strip formed of a 10 backing of asbestos cloth with a facing of flexible asbestos felt cemented to it by silicate of soda cement, and an exterior oppo-

sitely wound strip of asbestos cloth held in position by a fireproof cement.

3. A built-up covering of low heat conductivity for curved steam pipes and the like, which comprises in combination an interior spirally wound strip formed of a 15 backing of asbestos cloth with a facing of asbestos felt cemented to it by a fireproof cement and an exterior winding of wire held in place by an exterior layer of fireproof cement. 20

PHILIP C. JACOBS.
